United States Patent Office.

AUGUST HEIDELBERGER, OF NEW YORK, N. Y.

Design No. 2,561, dated January 22, 1867.

DESIGN FOR A TRADE MARK.

The Schedule referred to in these Letters Patent and making part of the same.

TO ALL WHOM IT MAY CONCERN:

Be it known that I, AUGUST HEIDELBERGER, of New York, in the county and State of New York, have originated and designed a new Design for Impression on Cigar-Boxes for a Trade Mark, of which the following is a full, clear, and exact description, reference being had to the accompanying drawings, making part of this specification.

I make two concentric circles, *a* and *b*, the one inside of the other. In the space formed by these two circles the word "superior" is placed at the top and the words "do Pedro Roger" at the bottom or lower side. Inside of the circle *a* the words "la Rosa de Santiago" and the word "Habana," in parenthesis, are arranged in such a manner that the word "Habana" will come in the middle at the bottom, and that the said words "la Rosa de Santiago (Habana)" form a complete circle concentric to the circle *a*. Into the circular space formed by these last-mentioned words a full-blown rose, *d*, is arranged on the top of a stem, *n*, inclining slightly toward the left hand; and a little below the same, on the right hand of the stem *n*, a rose-bud, *m*, is placed. Below these, two rose leaves, *s* *s*, are arranged, one on each side of the stem.

This design is executed in iron, or any other suitable metal, with all the lines, letters, and figures, as above described, raised above the surface, so that when heated the whole design can be burned into the wood of the cigar-box as a trade mark for a particular description of cigars packed into the box.

What I claim as my invention, and desire to secure by Letters Patent, is—

The design for a trade mark, as herein set forth and shown.

AUGUST HEIDELBERGER.
